CLAIM

The ornamental design for a planter, as shown and described.

DESCRIPTION

FIG. 1 is a top rear perspective view of a planter showing my new design.

FIG. 2 is a right side elevation view thereof.

FIG. 3 is a front elevation view thereof.

FIG. 4 is a left side elevation view thereof.

FIG. 5 is a back elevation view thereof.

FIG. 6 is a top plan view thereof.

FIG. 7 is a bottom plan view thereof; and,

FIG. 8 is another top rear perspective view thereof.

The broken lines in the drawings are included to show features in the environment that form no part of the claimed design.
